Des. 202,312
Patented Sept. 14, 1965

202,312

COMBINATION AIRCRAFT

Constantine A. Serriades, 3950 N. Lake Shore Drive,
Chicago, Ill.

Filed Nov. 27, 1964, Ser. No. 82,813

Term of patent 14 years

(Cl. D71—1)

FIG. 1

FIG. 2

~~FIG-3~~ 3

~~FIG-4~~ 4

FIGURE 1 is a top plan view of a combination aircraft showing my new design;
FIGURE 2 is a side elevational view thereof;
FIGURE 3 is a front elevational view thereof; and
FIGURE 4 is a rear elevational view thereof.

I claim:

The ornamental design for a combination aircraft, substantially as shown.
